UNITED STATES PATENT OFFICE.

CHRISTOPHER M. BRIDGES, OF SAN FRANCISCO, CALIFORNIA, ASSIGNOR TO BRIDGES SANITARY FISH CONTAINER COMPANY OF CALIFORNIA, OF SAN FRANCISCO, CALIFORNIA, A CORPORATION OF CALIFORNIA.

FISH-PACKER AND CARTON.

1,219,237.

Specification of Letters Patent. Patented Mar. 13, 1917.

Application filed February 14, 1916. Serial No. 78,139.

To all whom it may concern:

Be it known that I, CHRISTOPHER M. BRIDGES, a citizen of the United States, residing in the city and county of San Francisco and State of California, have invented new and useful Improvements in Fish-Packers and Cartons, of which the following is a specification.

This invention relates to a method and apparatus for packing fish and game, and particularly to a holder having a temporary receiving case mounted therein in which the fish or game is packed. The invention also relates to a carton, and to means for delivering the packed fish or game to the carton.

The invention will hereinafter be more fully described having reference to the accompanying specifications and drawings, in which—

20 Figure 1 is a perspective view of the holder.

Fig. 2 is a similar view of the temporary packing case.

25 Fig. 3 is a similar view showing the packing case mounted in the holder.

Fig. 4 is a view of the clamp.

Fig. 5 is a view of the temporary packing case and the carton, showing the temporary case in position to be inserted in the carton.

30 Fig. 6 is a central, vertical, longitudinal section through the carton.

Referring to the drawings in detail, A indicates in general a right-angular shaped holder consisting of a bottom section 2, provided with up-turned flanges 3 and a right-angularly disposed end section 4, provided with flanges 5. B indicates in general a temporary receiving case. This case is open at one end, as at 6, but is otherwise provided with a front section 7, having a handle 8 pivotally attached thereto, and is furthermore provided with a bottom and side sections 9, the upper ends of which are turned in, as at 10 to form guide flanges, as will hereinafter be described.

The holder and temporary receiving case is particularly constructed to permit fish, game or the like to be packed previous to shipping or before they are finally placed in 50 a carton or shipping case, such as indicated at C. The temporary receiving case B is first placed in the holder to assume the position shown in Fig. 3. The flanges 3 will secure the case B in position on the base 2 and

the flanges 5 will support the outer ends 11 55 of the case from spreading, while the end section 4 will form a closure therefor. The fish or game may now be packed in the case B in a manner substantially as shown in Fig. 3. The clamp 12 is then slipped over the 60 outer ends of the side sections 9 to prevent said sides from spreading when the temporary receiving case is removed from the holder, to be placed in the carton, indicated at C. The case B may be removed from the 65 holder the moment the packing operation is completed, by raising it out thereof by means of the handle 8.

The case as a whole is then completely removed from the holder and inserted in the 70 open end of the carton C, as shown in Fig. 5. The two cases, that is the carton C and the receiving case B are then up-ended sufficiently to permit the packed fish here shown to slide out or leave the temporary receiving 75 case and as this is removed, to be again repacked. The fish thus removed will assume the same position in the carton as this is of practically the same inside diameter as the temporary receiving case B. It is then only 80 necessary to apply a head to the carton C of any suitable character.

As the present carton is constructed of ordinary tin, it is only necessary to apply a flanged head, such as indicated at 14 which 85 may be soldered to secure it against removal, and also to produce an air-tight seal for the carton. The carton may now be handled in any suitable manner, but is preferably placed in a refrigerator to freeze or reduce the temperature of the contents, particularly if the fish are to be shipped any distance.

The receiving case B may be used over and over again, and together with the holder may be constructed in any shape and size 95 most convenient to the goods handled.

The bottom section 2 of the holder is preferably provided with one or more perforations 15 to permit a drainage of the fish or other articles, while being packed. The 100 open space 16 formed in the receiving case permits the fish to be nicely packed as the whole interior of the case is open to access and the open end 6 permits the contents of the temporary case to be easily removed 105 when desired.

The temporary clamp 12 is only applied when the case B is lifted out of the holder

and into the carton and serves no other purpose than to prevent spreading of the sides, while being removed from the holder to the carton.

5 The materials and finish of the several parts of the device may otherwise be such as the judgment and experience of the manufacturer may dictate.

I wish it understood that various changes 10 in form, proportions and minor details of construction may be resorted to within the scope of the appended claims and that I do not wish to limit myself to the specific design and construction here shown.

15 Having thus described my invention, what I claim and desire to secure by Letters Patent is—

1. A temporary packing case and holder comprising a right-angular shaped supporting member having upwardly projecting flanges formed on its edges, and an open-ended drawer-shaped packing case adapted to be supported by the supporting member.

2. A temporary packing case and holder comprising a right-angular shaped supporting member having upwardly projecting flanges formed on its edges, and an open-ended drawer-shaped packing case adapted to be supported by the supporting member, 30 and a removable clamping member adapted to engage the sides of the packing case near the open end.

3. A temporary packing case and holder comprising a right-angular shaped supporting member, an end wall on said supporting

member, an open-ended, drawer-shaped packing case, and means for supporting said packing case on said supporting member with the open end of said case against the end wall of said supporting member. 40

4. A temporary packing case and holder comprising a right-angular, drawer-shaped supporting member, upwardly projecting flanges on said supporting member, an upwardly extending end wall on said supporting member, and an open-ended, drawer-shaped packing case adapted to rest in said supporting member with the sides and one end thereof in engagement with said flanges and the open end thereof in engagement 45 with said end wall of said supporting member.

5. A temporary packing case and holder comprising a right-angular shaped supporting member, an end wall on said supporting 50 member, an open-ended, drawer-shaped packing case, guide flanges on the top edges of said packing case, and means for supporting said packing case on said supporting member with the open end of said case 55 against the end wall of said supporting member.

In testimony whereof I have hereunto set my hand in the presence of two subscribing witnesses.

CHRISTOPHER M. BRIDGES.
